HEARING AID DEVICE

John B. Nelson, Mount Lebanon, and Willard C. Mason, Pittsburgh, Pa.

Application November 19, 1937; Serial No. 175,434

2 Claims. (Cl. 179—107)

Our present invention relates to that class of device used for restoring or partially restoring the hearing of individuals with impaired hearing and more particularly relates to a hearing aid device which will enable the wearer thereof to obtain improved reception of conversation and speaking while dampening or eliminating extraneous or interfering noises.

Hearing aid devices of the general type herein involved have been known for some years and have made it possible for persons with impaired hearing to compensate, at least partially, for such loss in hearing. Developments along the line of improved hearing aid devices have generally taken the form of supplying more power and greater sensitivity and remarkable strides have been made in this direction. With increasing power and sensitivity, however, a new disadvantage has arisen in connection with hearing aid devices in that these devices are too sensitive to all types of sound waves, thereby causing the wearer of the device considerable difficulty and inconvenience as well as discomfort due to the fact that these devices pick up sound waves and noises which interfere with proper hearing of speaking or conversational tones. This situation has given rise to so much discomfort to the wearers of the devices that in many cases use of the devices had to be abandoned or utilized only under special conditions.

It is, accordingly, one of the objects of our present invention to produce a hearing aid device which, without sacrificing desired power and sensitivity, will improve hearing by limiting the intensity or volume of sound transmitted to the auditory ear canal to a predetermined constant maximum which will not cause discomfort to the wearer thereof.

Another object of our invention resides in producing a hearing aid device which dampens or excludes sound waves or tones beyond a certain predetermined frequency range, thus permitting sound waves or tones within a desired frequency range to be heard with greater clarity and distinctness.

A further object of our invention resides in so modifying that portion of a hearing aid device which is at or adjacent the wearer's ear that sound waves or tones within the normal or usual conversational or speaking range will be clearly heard while at the same time dampening or eliminating sound waves or noises having frequencies beyond such range.

More specifically, our invention provides a novel construction and arrangement in connec-

tion with the diaphragm construction utilized in that portion of the hearing aid device at or adjacent the wearer's ear and this construction is in the form of a double diaphragm with a liquid therebetween.

Other and further objects and advantages will be understood by those skilled in this art or will be apparent or pointed out hereinafter.

In the accompanying drawing:

10 Figure 1 illustrates in section a device embodying the present invention and also includes diagrammatically the general arrangement of hearing aid device systems;

15 Fig. 2 is an exploded view partly in side elevation and partly in vertical section showing our invention on an enlarged scale; and

Fig. 3 is a perspective view of the lower portion of Fig. 2.

Like numerals designate corresponding parts in the various views of the drawing.

The hearing aid system is made up of a suitable battery 10, a suitable microphone 11, a rheostat 12, and a head phone 13. The battery, microphone and rheostat may be of any known or approved types such as those now used and per se form no part of the present invention.

Likewise, the mode of operation of these hearing aid devices is well known but for the purposes of convenience will be briefly referred to here.

30 Sound waves or vibrations in the air as they emanate from any source or sources cause a diaphragm in the microphone 11 to vibrate in response thereto. Vibrations of the microphone diaphragm cause vibrations in physical and/or

35 pressure conditions within the microphone and these changes in condition alter the electrical resistance of the microphone. The changes in the microphone resistance are in accordance with the vibrations or sound waves set up from the source and cause corresponding changes in battery current flowing through the microphone and the head phone coil. Thus in effect the microphone acts as a valve, operated by the sound waves, which controls the battery current. Vari-

10 tions in battery current through the head phone coil cause magnetic attraction of the head phone magnet for the head phone diaphragm to effect changes which therefore are in accordance with the changes in vibrations or sound waves emanating from the source or sources. Conse-

15 quently, the varying pull on the head phone diaphragm sets up corresponding vibrations in such diaphragm and thus causes corresponding variations in pressure of the air in the auditory canal of the ear. These air vibrations in the auditory

canal correspond to those emanating from the source except that the microphone has greatly amplified the same.

It will readily be understood from the foregoing explanation of the operation of these devices that the greater the power and/or sensitivity of the hearing aid devices the worse the device becomes insofar as extraneous noises are concerned. By extraneous noises we mean those noises which form no part of what the wearer of the device wishes to hear. For example, if the wearer wishes to hear ordinary speaking or conversational tones, the extraneous noises will include such noises as those resulting from traffic, electrical appliances, or those noises arising from various other sources. We have found that most of these extraneous noises are of higher pitch or frequency than conversational or talking tones. The hearing aid devices now known and used amplify the higher pitched noises to an uncomfortable extent and so as in many cases to prevent the wearer of the device from being able to distinguish speech or conversation due to the interference and the louder quality of the extraneous noises.

In terms of frequency (vibration frequency) the conversation or speech range is generally accepted as including the range from 256 to 2048 vibrations per second which is that range generally designated with reference to the keyboard of a piano as extending from middle C to the third octave above middle C and termed C^{IV}. In the frequency above the speech range will be found many musical notes and tones as well as noises arising from traffic, electrical equipment and many other types of extraneous noises, particularly those emanating from metallic contacts.

Our invention limits the volume or intensity output to a substantially constant maximum and dampens those frequencies above the speech range to an extent which prevents such from interfering with hearing speech and conversation while not appreciably impairing the efficiency of the hearing aid device as to the receiving of speech and conversational tones. In other words, the sound waves of frequency above 2048 are dampened to a much greater extent than those within the speech range and by comparison the speech range is received much more clearly and distinctly than is possible with present devices. Loud or irritating sounds and noises are cut down to a comfortable value.

The head phone 13 is made up of two main parts 14 and 15. The part 14 is comprised of a casing 16 provided with a core 17 with an electrical winding 18 therearound and a magnetic element 19 provided with three cobalt steel magnets 20 spaced at 120° intervals. This portion of the hearing aid device is likewise conventional. Casing 16 is provided with a threaded extension 21. The portion 15, embodying our present invention, comprises a cylindrical portion 22 internally threaded at 23 connected to and merging with a second and smaller cylindrical portion 24 also internally threaded as at 25. Portions 22 and 24 are connected by the annular metal portion 26.

The lower end of this latter cylindrical portion 24 is substantially closed by end member 27, there being, however, a central aperture 28 therein and surrounding this central aperture is an attachment element somewhat similar to a snap fastener button as designated by the numeral 29 and this has an aperture 30 aligned with the aperture 28 aforesaid. This permits detachable connection with the ear piece 30

which is shaped individually for each ear and serves to maintain the device in proper position with relation to the auditory canal of the ear.

Disposed within the larger cylindrical portion

5 24 is a thin steel diaphragm 31 which is in the form of a disc having a thickness of approximately .001 inch. This may be made of any suitable steel providing the requisite properties such as stainless steel. Soldered, brazed or otherwise secured to this diaphragm is the plate member 32 which responds to the pull of the magnets within the casing 16 and thus which sets up vibrations of the diaphragm 31 corresponding to the sound waves which the source propagates. This diaphragm is secured in place at or about the bottom of the cylindrical portion 15 22 by means of a ring or annulus 33 which passes over the threads 23 and firmly holds the diaphragm in position.

20 At or about the upper end of the smaller cylindrical portion 24 is another diaphragm which is indicated by the numeral 34 and which is of the same steel as the diaphragm 31 and which also is of the same thickness. This latter diaphragm 34 is suitably secured or immobilized in position between two rings or annuli 35.

25 Between the two diaphragms a liquid is placed, as designated at 36. This liquid is preferably distilled water but we are not restricted solely to water as we find that other liquids are also satisfactory. The major considerations in connection with the liquid between the diaphragms are that (1) the liquid must be incompressible, (2) the liquid must have little or no volume change within the temperature range encountered between the coldest winter day and the hottest summer day, (3) the liquid must be unchangeable in its characteristics, i. e., stable, (4) the liquid must be non-corrosive, and (5) the liquid must have the capacity to dampen sound waves and to limit the volume or intensity of the sound output of the device. We find that while water serves satisfactorily, distilled water being somewhat better than tap water, a small proportion of alcohol may be added to prevent freezing in cold weather and the proportions of water to alcohol are such that the mixture will not freeze at say 20° below zero. We may, however, use a mixture of about 50 per cent glycerine and about 50 per cent water or so-called hydraulic brake oil which we understand is composed of a mixture of castor oil and alcohol as well as other mixtures which meet the above conditions and the use of the word "liquid" hereinafter is intended to include the foregoing and other liquids which have the properties and characteristics above noted.

30 The casing 16 of part 14 of the headphone or earphone 13 has a plug extension 37 to connect wires 38 as shown. Figure 1 shows also a typical circuit used in a hearing aid device. In assembling the part 15 either diaphragm is placed in position first and secured in place by the securing means shown for that purpose. Then the space which subsequently forms the chamber when the other diaphragm is positioned is overfilled with the water or other liquid used and then the other diaphragm is positioned and secured in place, excess water being displaced by the act of positioning the second diaphragm and hence in this way complete filling of the chamber with liquid is insured while at the same time preventing any air pockets or air bubbles from being formed or trapped in the chamber. It will be understood that when the top diaphragm is placed in position first the part 15 is

inverted during the time that the liquid is introduced and the second diaphragm positioned.

Our invention therefore resides chiefly in the provision of a double diaphragm with a liquid as above defined therebetween and in actual practice the diaphragms are of such size and spacing that only a few drops of liquid are required to fill the chamber thereby produced. Of course changes in the liquid used in any given instance affects the dampening nature of our invention but we so select that liquid as to produce little or no diminution of volume of sound waves having a frequency within the speech range while at the same time considerably dampening sound waves having frequencies above the speech range. Different liquids also enable somewhat modified results to be produced so as to adapt the invention to various conditions of impaired hearing. This cannot be done by present devices.

We find that our structure is such that the higher the frequency of the sound wave and the louder the noise the more it is damped and hence metallic noises, noises from traffic or electrical equipment are very greatly diminished with consequent marked improvement in the quality and clarity of sound waves within the speech range. Frequencies below the speech range are also somewhat affected but these are ordinarily not such as interfere with hearing when using a hearing aid device. Sharp or rasping noises are softened, however, regardless of their frequency.

In actual practice use of our modified hearing aid device has improved the capacity of those with impaired hearing to distinguish speech and conversational tones with marked facility. The utility of the device is broad, therefore, and whether the wearer is utilizing the same on the street, in a restaurant, or in any more or less noisy locality the results herein set forth are adequately accomplished.

The above is intended more as illustrative than as limitative and we may make certain variations, substitutions, additions or omissions without departing from the scope and principles of the invention. The various portions of the device which are associated with the ear may be made of any desired metallic or non-metallic material and of such size and configuration as will best suit circumstances of use. While we have shown diaphragms of different size, this is not intended to constitute a limitation upon our invention because the use of differently sized diaphragms is more or less necessitated by space and size limitations in connection with a human ear. Our invention may, therefore, assume different specific forms and all such changes are deemed to be a part of the present invention and to be covered by the appended claims.

While specifically designed for hearing aid devices our invention is applicable to amplifying devices, speakers or systems having similar or analogous uses or wherever the principles thereof find application. While we have set forth a preferred diaphragm thickness of .001 inch, we find that, depending upon conditions and the results to be produced, we may utilize a diaphragm having a thickness within the range of approximately .001 inch-.003 inch. In one particular case we have used a diaphragm .00150 inch in thickness with entire success. While we prefer a steel diaphragm we intend to include within the scope of our invention diaphragms of other suitable materials whether metallic or non-metallic.

Having thus described our invention, what we claim as new and desire to secure by Letters Patent is:

1. In a hearing aid device, an internally threaded cylindrical portion, a steel diaphragm approximately .001 inch thick disposed in said cylindrical portion, a central magnetic plate secured to said diaphragm, means for holding said diaphragm in proper position in said cylindrical portion, a second internally threaded cylindrical portion integral with said first cylindrical portion, a steel diaphragm approximately .001 inch thick disposed in said second cylindrical portion, means for maintaining the same in proper position therein and an incompressible vibration dampening liquid confined between said diaphragms.
2. In a hearing aid device, a headphone comprising a casing having a threaded extension and a cylindrical portion which is internally threaded for engagement with the threaded extension of the casing, said casing being provided with a core having an electrical winding therearound and a magnetic element operatively associated with said core and winding and having spaced magnets symmetrically disposed with respect to said core, said cylindrical portion having a cylindrical extension integral therewith, a thin steel diaphragm in said cylindrical portion and a second thin steel diaphragm in said cylindrical extension, an incompressible liquid completely filling the space between said diaphragms, means to hold each diaphragm in place so that it is in effect supported only at its periphery, a plate member secured to one of said diaphragms and means for transmitting air vibrations from said other diaphragm to the auditory canal of an ear in such manner that vibrations having a frequency in excess of 2048 vibrations per second are damped.

CERTIFICATE OF CORRECTION.

Patent No. 2,266,788.

December 23, 1941.

JOHN B. NELSON, ET AL.

It is hereby certified that error appears in the printed specification of the above numbered patent requiring correction as follows: Page 1, second column, line 34, for "vibrations" read --variations--; page 2, first column, line 29, for "vibartions" read --vibrations--; and that the said Letters Patent should be read with this correction therein that the same may conform to the record of the case in the Patent Office.

Signed and sealed this 17th day of February, A. D. 1942.

(Seal)

Henry Van Arsdale,
Acting Commissioner of Patents.
